(57) **CLAIM**

The ornamental design for a belt, as shown and described.

DESCRIPTION

FIG. 1 is a perspective view of a belt of my new design; FIG. 2 is a side elevational view of the belt of FIG. 1; FIG. 3 is a top plan view of the belt of FIG. 1; and, FIG. 4 is a bottom plan view of the belt of FIG. 1. The broken line portions of the drawings are included for the purpose of illustrating unclaimed structure and form no part of the claimed design.

1 Claim, 4 Drawing Sheets*FIG. 1*

FIG. 2

FIG. 3

FIG. 4
